VLADIMIR S. BEKOFSKY, OF JENCHUAN, COREA.

BALANCED COOKING-STOVE.

SPECIFICATION forming part of Letters Patent No. 355,498, dated January 4, 1887.

Application filed June 14, 1886. Serial No. 205,072. (No model.)

To all whom it may concern:

Be it known that I, VLADIMIR S. BEKOF-
SKY, of Jenchuan, Corea, have invented a new
and Improved Balanced Cooking-Stove, of
5 which the following is a full, clear, and exact
description.

The object of my invention is to provide a
practical balanced stove designed particularly
for use on shipboard, the stove being accu-
10 rately equposed on its base or support, so that
the stove proper will always maintain a hori-
zontal position, no matter to what extent the
ship may roll.

The invention consists, principally, in piv-
15 otting the body of the stove on a hollow base
or support that constitutes the chimney to the
stove.

The invention consists of the construction,
arrangement, and combination of parts, as here-
20 inafter described and claimed.

Reference is to be had to the accompanying
drawings, forming a part of this specification,
in which similar letters of reference indicate
corresponding parts in all the figures.

25 Figure 1 is a broken plan view of my im-
proved balanced stove. Fig. 2 is a sectional
elevation of the same, taken on the line $x-x$ of
Fig. 1. Fig. 3 is a transverse sectional eleva-
30 tion taken on the line $y-y$ of Fig. 2. Fig. 4 is
a plan view of the upper end or top of the
support, the same being constructed in semi-
spherical form; and Fig. 5 shows a modifica-
45 tion of the upper end of the support made in
semi-cylindrical form.

35 The frame of the stove is constructed to form
the fire-box A, the ash-pit B, and the separate
oven C at the opposite end of the stove. The
oven C is separated from the fire-box by the
central space or chamber, D, which incloses
40 the upper end of the base or support E. The
fire-box A and the oven C are joined to the
top plate, F, which is made integral with or
is provided with a hollow ball, G, which is
45 open at the top and bottom and fits in the semi-
spherical seat or cup E' of the base or stand-
ard E. On the top of the plate F are formed
two ribs, H H', and a cross-rib, H', which form
50 a flue or passage, J, for conducting the pro-
ducts of combustion to the entrance h of the hol-
low ball G. These ribs also serve to strengthen
the stove.

Covering the fire-box A, the oven C, and the

ribs H H' is the cast-iron plate I, formed with
the stove-holes I'. The concave portion or
seat E' of the stand E, which receives the ball
55 G, (and thus pivotally supports the stove,) has
the opening e formed in the middle thereof
to correspond with the opening h, and numer-
ous openings, e', are formed in said concave
surface, as shown clearly in Fig. 4, so that the
60 draft will not be impeded. The opening e is
a continuation of the hollow body of the sup-
port or stand E, so that said stand constitutes
the chimney of the stove, and connected to
the bottom of the stand is the horizontal pipe
65 E', which extends as far as convenient, and to
which a vertical pipe may be connected by an
elbow or other suitable joint, as shown in Fig.
70 3; and to prevent burning of the deck I form
an air-space, E'', below the horizontal portion
E' of the chimney, through which air-space
air can freely circulate, as will be understood
from Fig. 3.

The flame and products of combustion from
the fire-box A may be caused to pass directly
75 into the flue J, and thence to the chimney, as
indicated by the arrows in Fig. 1; or they may
be caused to pass through the spaces C' C'',
surrounding the oven C, and thence to the flue
J, as indicated by the arrows in Fig. 2. To
80 turn the flame and products of combustion
into the spaces surrounding the oven, the
damper h must be turned to a vertical pos-
ition, as shown in Fig. 2, which closes the
85 mouth of the flue J, and to cause the flame and
products of combustion to pass directly
through the flue J said damper must be turned
to a horizontal position to close the vertical
space C'' at the back of the oven.

Between the fire-box A and the oven C are
90 formed boxes L L', which may be closed by the
doors L', and which receive heat from the fire-
box, oven, and top plate, I, and radiated heat
from the hollow ball G, so that they serve as
warming-ovens, which may be used for heat-
95 ing plates, &c. The back and bottom plates,
which form the warming-boxes L, also consti-
tute brace-plates for strengthening the stove.
From the top of the stove rise the arms M,
which support the rods N, which may be
notched at their upper edges, and on these
rods are placed two movable weights, O. These
weights are provided with open hooks, so that
they can be easily shifted upon the rods N and

easily removed from said rods and placed upon the opposite side of the stove, or opposite any kettle or pan placed upon the stove, for properly counterbalancing and keeping the stove 5 in an upright position.

Instead of using the hollow ball G and semi-spherical cup to receive the same, as shown in Figs. 2, 3, and 4, I may use a cylindrical or semi-cylindrical connection, as shown in Fig.

- 10 5. With the former arrangement the stove is pivoted universally, while with the latter the stove will tip only in two directions. When the stove stands at an angle to the support E, the lower opening, h', in the ball G will be partially closed by the sides of the cup E', which tends to interfere with the draft. To avoid this the cup portion E' is provided in its sides with numerous openings, e', sufficient in number and size, so the aggregate area of the openings in the cup E' will never be less than the sectional area of the support E, in consequence of which the draft will be constant. The horizontal part E² of the chimney has a small pocket, P, formed in it immediately below the 20 hollow support E, for accumulating any soot or ashes that may pass down from the stove, and one end of the fire-box A may have a transverse partition, m, fitted in it to form a water-heating reservoir at one end of the fire-box, from which reservoir water may be drawn 25 through the cock m'.

On smooth water the stove may be chained to the deck by four chains, Q; or, in place of these chains, four legs, R', may be used for holding the stove in an upright position, and the latter may be constructed to be readily detached from the stove or to move vertically in guides, and provided each with a set-screw, b, for securing the leg in elevated position.

- 30 40. The space surrounding the oven C may easily be cleaned through the small opening d, and the vertical portion of the chimney or hollow support E and the hollow ball G may be cleaned through the central opening, i, in the top plate, I.

By constructing the stove as described the same is accurately balanced upon its stand, so as always to maintain a horizontal position irrespective of any inclination of its support E, and every part of the stove is easily accessible for cleaning, and as the warming-chambers L L, between the fire-box and the oven, retain a large part of the radiated heat and confine it in the central space, D, the stove will be much 45 5 more economical in its consumption of fuel than any common stove of the same dimensions; and, besides, the stove is cheap to manu-

facture and easy to manage, and while being balanced to always maintain its level on ship-board it has a central draft, and all direct connection of the stove with a pipe off from the center of the stove is avoided.

Having thus fully described my invention, I claim as new and desire to secure by Letters Patent—

1. The combination of a pivoted or balanced stove and a hollow vertical support constituting a flue, and arranged centrally, or substantially so, to the main body of the stove, substantially as described.

2. The hollow vertical support or stand E, formed with a socket at its upper end and constituting a flue, in combination with the stove pivoted in said socket upon a hollow bearing, substantially as described.

3. The stove provided with the hollow ball G, having openings h h', in combination with the hollow base E, having the open or grated socket E', substantially as described.

4. The hollow support E, having the horizontal extension E², in combination with the stove pivoted upon the support, substantially as described.

5. The fire-box A and oven C, arranged at opposite ends of the stove, in combination with the horizontal flue J, joining the central vertical chimney-base, E, and the partition H', cutting off the entrance to the fire-box from the flue J, substantially as described.

6. The oven C, having the surrounding spaces C' C², combined with the fire-box, the flue J, and the central chimney-support, E, substantially as described.

7. The oven C, having the surrounding spaces C' C², in combination with the flue J, central chimney-base, E, and damper k, arranged to close flue J and space C', substantially as described.

8. The body of the stove pivoted centrally upon a vertical hollow base and provided with the side rods, N, in combination with the movable weights O, placed upon said rods, substantially as and for the purposes set forth.

9. The hollow vertical support E, connected with the horizontal extension E², in combination with the body of the stove pivoted upon the vertical support E, and the air-flue E³, formed below the horizontal extension E², substantially as and for the purposes set forth.

VLADIMIR S. BEKOFSKY.
